UNITED STATES PATENT OFFICE.

MATTHEW WIARD, OF PHILADELPHIA, PENNSYLVANIA.

DESIGN FOR CARRIAGE-DOOR FENDER.

SPECIFICATION forming part of Design No. 11,805, dated June 1, 1880.

Application filed February 25, 1880. Term of patent 3½ years.

To all whom it may concern:

Be it known that I, MATTHEW WIARD, of Philadelphia, in the county of Philadelphia and State of Pennsylvania, have invented an Improvement in Designs for Carriage-Door Fenders, of which the following is a specification.

My invention relates to that class of iron-work known as "carriage-door fenders," and especially designed for stables; and it consists in constructing a fender of iron or other base metal, and giving to it a shape which may represent a portion of a leg of a horse, and also in filling in the space between the leg and the wall by an ornamented or plain casting, with a flange on either side of same, which has in it lugs, through which bolts pass to secure the fender to the building.

The object of my invention is to make a carriage-door fender having a design which makes it handsome and at the same time appropriate to the use to which it is put.

In the drawings, Figure 1 is a perspective view of my improved carriage-door fender. Fig. 2 is a section of same through the line xx , Fig. 1.

Like letters of reference correspond to like parts.

A in the drawings shows a horse's leg from the knee down. B B are flanges, which rest

against the wall of the doorway, to which the fender is secured by bolts, which pass through lugs C C and hole D. The space between the flanges B B and leg A is filled with open-work E.

35

The bottom of the hoof has projections K K, which are secured in the ground.

There is no drilling or other expensive finishing on these castings.

Having now described my invention, what 40 I claim as new, and desire to secure by Letters Patent, is—

1. The design, in a carriage-door fender, of the horse's leg, in combination with the flange supplied with the slots or holes, substantially 45 as shown.

2. The design for a carriage-door fender, consisting of the combination of the leg A, the projections K K, and the open work E, substantially as and for the purpose specified. 50

3. The design for a carriage-door fender, consisting of the leg A, in combination with open work E, flanges B B, and lugs C C, substantially as and for the purpose specified.

In testimony of which invention I hereunto 55 set my hand.

MATTHEW WIARD.
